Attorney.

UNITED STATES PATENT OFFICE.

ASMUS PETERSEN, OF ST. LOUIS, MISSOURI.

TROLLEY-POLE ADJUSTER.

1,420,859.

Specification of Letters Patent. Patented June 27, 1922.

Application filed September 29, 1919. Serial No. 327,132.

To all whom it may concern:

Be it known that I, ASMUS PETERSEN, a citizen of the United States, residing in the city of St. Louis and State of Missouri, have 5 invented certain new and novel Improvements in Trolley-Pole Adjusters, of which the following is a specification.

My invention relates to trolley-pole adjusters, and has for its object to provide a 10 device adapted to be applied to a trolley-pole adjacent the trolley wheel and so constructed that a movable member thereof may be actuated by pulling on the trolley-rope for quickly replacing the trolley-wheel in 15 contact with the trolley-wire after it has left the trolley-wire.

With the above and other objects in view, the invention consists in the novel construction, arrangement and combination of parts, 20 hereinafter described and finally pointed out in the claims hereto appended.

Referring to the accompanying drawings forming a part of this specification wherein like characters of reference denote similar 25 parts throughout the several views:

Fig. 1, is a side elevation of a trolley-pole equipped with my improvement, the same being shown in its normal position in full lines, and in its uppermost adjusted position in dotted lines.

Fig. 2, is a detail of the forward extension end of the movable guide member.

Fig. 3, is a top plan view of Fig. 1.

Referring to the drawings, the reference 35 character 1 designates a trolley-pole. 2, a socket member fixed to the trolley-pole having a bifurcated end 3. 4, a trolley-wheel rotatably mounted in the bifurcated end 3 of the socket member 2. 5, is the usual trolley-rope fixed to the socket member 2 for actuating the trolley-pole 1, and 6 indicates the trolley-wire.

In carrying out the aim of my present invention, I employ a pair of suitable clamp-members 7 and 8, which are securely held in a clamped position upon the socket-member 2 by means of the fastening devices 9. Each clamp-member 7 and 8 is provided with a stop, or lip 10 adapted to engage the shoulder 11 of the socket-member 2 to prevent any possible change of the clamp-members 7 and 8 from slipping down the socket-member, should the fastening devices 9 loosen a little from any cause.

55 A relatively long movable guide member 12 having an opening 13 is pivotally con-

nected to the ears 14 of the clamp member 8, by means of the pin 15. The rear end of the guide member 12 is provided with a pair of outwardly diverging guide arms 16. 60

The forward end of the guide member 12 is provided with an extension member 17 having an opening 18 and the forward extremity 19 of the extension member 17 is provided with a rope opening 20. The extension 65 17 is arranged at a suitable angle to the longitudinal axis of the guide member 12, while a rope opening 20 is also arranged at a suitable angle to the longitudinal axis of the extension member 17. 70

The trolley-rope 5, fixed to the socket member 2, first passes through the opening 18, of the extension member 17 and through the opening 20, as clearly shown in Fig. 1.

The device normally assumes the position 75 shown in full lines in Fig. 1, with the guide-arms 12 extending downwardly and rearwardly from the pivot connection 15 and with the extension member 17 extending forward from the pivot connection 15 in a substantially horizontal position. 80

Assuming that the trolley-wheel 4 has left the trolley-wire 6, the trolley-wire will, due to the upper movement of the trolley wheel, come into contact with one of the spreading 85 guiding arms 16, thus preventing the trolley wheel from rising to a higher elevation. Now, all that is necessary for the conductor to do to replace the trolley-wire 6 upon the trolley-wheel 4, is to pull rearwardly upon 90 the trolley rope 5, which will cause the trolley-pole to stand still while at the same time the pulling movement on the rope will bring the extension member 17 to the substantially vertical position shown in Fig. 1 and thereby 95 in turn raise the guide-member 12 and diverging guide-arms 16 to the upwardly and rearwardly inclined position shown in Fig. 1. The upper movement of the guide arms 16 will cause the trolley-wire 4 to be raised 100 at the same time, and the guide arms 16, in being raised, will gradually crowd the trolley-wire 4 to the center of the guide-arms so that by the time the arms have been fully raised the trolley will be in alignment with 105 the groove of the trolley wheel. Now, as the trolley rope 5 is slackened after the trolley-wire 4 has been raised by the guide arms 16, the trolley-pole, when released will rise and the trolley-wire will ride in the 110 groove of the trolley-wheel, as is manifest.

From the foregoing, it is evident that

when the trolley wheel 4 jumps out of engagement with the trolley-wire 6, that to replace the trolley-wire upon the trolley wheel, the operator merely pulls rearwardly 5 on the trolley-rope 5 which causes the guide arms 16 to raise the trolley wire and bring it into a center line with the groove of the trolley-wheel where it will seat itself again after the trolley-pole has been permitted to 10 raise by letting loose of the trolley-pole 5.

It will be observed that the arms of the bifurcated end 3 of the trolley-pole will act as a stop for the members 12 to engage when the device is actuated so as to limit 15 the upward movement of the members 12. This is clearly shown in dotted lines in Fig. 1. When the arms 12 are in the position shown in dotted lines in Fig. 1, it will be 20 observed that part of the trolley-wheel 4 passes through the opening 13.

The many advantages of the herein described invention will readily suggest themselves to those skilled in the art to which it appertains.

I do not desire to be understood as limiting myself to the details of construction and arrangement as herein described and illustrated, as it is manifest that variations and modifications may be made in the features 25 of construction and arrangement in the adaptation of the device to various conditions of use without departing from the spirit and scope of my invention and the terms of the following claims, hence I wish 30 it to be understood that I reserve the right to make any such changes or modifications as may fairly fall within the scope of the appended claims when fairly construed.

What I claim is:

1. In means for replacing a trolley-wire upon a trolley-wheel, an angular movable

member pivotally connected to a trolley-pole and having an opening to receive the trolley-wheel while replacing a trolley-wire thereon, outwardly diverging arms formed at the 45 rear end of the movable member adapted for engagement with the trolley-wire after the trolley-wheel has left the trolley-wire, the forward end of said angular movable member being provided with a double loop, a 50 trolley-rope fixed at one end to the trolley-pole and passing through the double loop of the movable member to provide a slipping rope connection when the forward end of the movable member is pulled downwardly 55 and rearwardly for raising the forked end of the angular movable member into contact with trolley-wire for replacing the trolley-wire upon the trolley-wheel.

2. In combination with a trolley-pole and 60 trolley-wheel, a guide member pivotally connected to the trolley-pole, said guide member having a pair of rearwardly and downwardly extending spaced arms to form an opening for the trolley-wheel to enter when 65 elevated, forked arms extending from the free ends of said spaced arms, said guide member having a pair of forwardly extending diverging arms forming a rope loop and terminating downwardly and forwardly to 70 form a second loop through which loops a trolley-rope is adapted to pass for connection with the trolley-pole so that when the rope is pulled rearwardly it will slip in the rope loops and at the same time lower the forward 75 end of the guide member and raise the rear end thereof to an elevated position for replacing a trolley-wire upon the trolley-wheel.

In testimony whereof, I have hereunto 80 signed my name to the specification.

ASMUS PETERSEN.
